UNITED STATES PATENT OFFICE

2,473,992

ELECTRIC SWITCH

John Fowler, Stockport, England, assignor, by
mesne assignments to General Electric Company, a corporation of New York.

Application September 6, 1946, Serial No. 695,184
In Great Britain August 1, 1945

Section 1, Public Law 690; August 8, 1946
Patent expires August 1, 1965

1 Claim. (Cl. 200—5)

1

This invention relates to electric switches and more particularly to improvements in the operation of arcing duty switching mechanisms for load ratio control systems.

In a load ratio control system, taps are changed on a winding, usually a transformer winding, while the winding is carrying current and without interrupting the current. In many systems of this kind, there are non-arcing duty tap changing switches combined with an arcing duty switching mechanism which transfers the current without interrupting it from one tap changing switch to the other preliminary to the operation of the tap changing switch from which the current is transferred or diverted.

In accordance with this invention, there is provided an improved arcing duty switching mechanism which is especially adapted for operation on high voltage circuits and which has simple, direct and positive actuating means of inexpensive construction. The switch is further characterized by ease of replacement of its contact surfaces. In a sense, it consists of four switches and a novel actuating mechanism for causing the switches to operate in a predetermined cycle.

An object of the invention is to provide a new and improved electric switching mechanism.

Another object of the invention is to provide a new and improved operating mechanism for load ratio control system arcing duty contactors.

The invention will be better understood from the following description taken in connection with the accompanying drawing and its scope will be pointed out in the appended claim.

In the drawing, Fig. 1 is a perspective view of an embodiment of the invention and Fig. 2 is a circuit diagram illustrating how the switch shown in Fig. 1 may be connected in the load ratio control system.

Referring now to the drawing, and more particularly to Fig. 1, the switching mechanism shown therein may be housed in a closed compartment, a portion of one wall of which is indicated at 1. Passing through this wall is an insulating bushing 2 for a conductor 3. Pivotally mounted on the end of the conductor 3 are four switch arms 4, 5, 6, and 7. These arms may, for example, all be rotatable about a shaft 8 which passes through the end of the conductor 3. Each arm terminates in a movable contact all of which may be similar and which are designated by the reference numeral 9. They are pivotally mounted at 10 on their respective arms and are biased upwardly by means of springs 11.

Cooperating with each movable contact is a fixed contact 12 and the four fixed contacts 12 are mounted on separate insulating bushings 13, 14, 15, and 16 which pass through the wall 1 of the switch compartment.

2

The above-described switches are single pole, single throw switches. They are operated in the proper sequence or cycle by means of an operating mechanism consisting of a rotatably mounted oscillator member 17 to which are fixedly attached four angularly displaced crank arms 18, 19, 20 and 21. A connecting rod 22 interconnects the crank 18 and a backward extension of the switch arm 5. Similarly, a connecting rod 23 interconnects the crank 19 and the switch arm 6, a connecting rod 24 interconnects the crank 20 and the switch arm 7, and a connecting rod 25 interconnects the crank 21 and the switch arm 8.

Member 17 is oscillated through the angle indicated in Fig. 2 in any suitable manner such as by means of a fifth crank 26 which is connected by means of a connecting rod 27 to a pin on a rotatable driving member 28 so that a continuous rotation of the member 28 will cause the desired angular degree of oscillation of the member 17.

The purpose of yieldably mounting movable contacts 9 on their respective contact arms is to permit a certain degree of movement of these contact arms after the contacts of each switch come into engagement.

The operation of the switching mechanism shown in Fig. 1 is as follows. The mechanism is illustrated at one end of its arc of oscillation in which the switches which have arms 4 and 5 are open and the switches which have arms 6 and 7 are closed. The crank 20, which actuates the switch arm 6, is pointed vertically downward and the movable contact 9 on the switch arm 6 has been pivoted considerably around its mounting point whereas the crank arm 21 which operates the switch arm 7, is on one side of the lowermost dead center but the movable contact on the end of the arm 7 is in engagement with its fixed contact although the latter has not been pivoted as far around its mounting as is the case with the movable contact on the arm 6.

As the member 17 rotates counter-clockwise, the switch having the contact arm 7 will first open. Next, the switch having the contact arm 5 will close so that the two switches having contact arms 5 and 6 will now be closed and the other two switches will be open. This will correspond to an angular position of the member 17 in which the cranks 19 and 20 are substantially symmetrically located relative to a vertical center line through the member 17. As the member 17 continues to rotate counter-clockwise, the switch having the contact arm 6 will open. During this latter movement, the contact 10 on the arm 5 will be pivoting about its mounting due to the continued downward movement of the crank 19 and when the end of the range of counter-clockwise angular movement of the member 17 is ap-

proached, the switch having the contact arm 4 will close.

During the return movement of the oscillatory member 17, the operating cycle of the switch is reversed, the switch having the arm 4 opening first, then the switch having the contact arm 6 closing next followed by the opening of the switch having the arm 5 and finally the closing of the switch having the arm 7 so that the mechanism is restored to the position shown in the drawing.

Fig. 2 illustrates how the electrical connections of the switching mechanism shown in Fig. 1 may be made. Conductor 3 may be one of the line conductors of a transformer winding 29 which has a plurality of taps 30, 31, 32, 33, 34, 35, 36, 37 and 38. A tap changing switch 39 is arranged to make selective engagement with the odd numbered taps and a tap changing switch 40 is arranged to make selective engagement with the even numbered taps. For cooperating with the arcing duty switching mechanism for the purpose of preventing a momentary short circuit of portions of the winding 29 between adjacent taps thereof during operation of the switching mechanism, a pair of impedance elements 41 and 42 are connected respectively to the tap changers 39 and 40. These impedance elements may be either reactors or resistors. In Fig. 2, the four single pole, single throw switches have been designated merely by the reference numerals of their respective movable operating arms in Fig. 1. It will be seen that the arms are directly connected to the conductor 3, as in Fig. 1. The impedance element 41 is permanently connected between the fixed contacts of the switches which have operating arms 4 and 5 and the impedance element 42 is permanently connected between the fixed contacts of the switches which have operating arms 6 and 7. The positions of the switches correspond to those of Fig. 1 in which the switches having arms 6 and 7 are closed and the other two are open so that all load current of the winding 29 passes through the switch 7 and the impedance 42 is short circuited. In this position on the circuit, tap changer 39 carries no current and consequently it can be moved to tap 33 without in any way affecting the current in the circuit. If now it is desired to transfer the circuit current to tap changer 39 from tap changer 40, the switch mechanism is operated in the manner described above. Thus, the opening of the switch 7 causes the load current to flow through the impedance 42, the closing of the switch 5 connects impedances 41 and 42 in series between adjacent taps in the main winding, the opening of the switch 6 diverts all of the circuit current through the tap changer 39, the impedance 41 and the switch 5. The closing of the switch 4 short circuits the impedance 41 and permits all of the current to flow through the switch 4.

In practice, the tap changers 39 and 40 will be mechanically driven from the rotatable member 28 in any suitable manner (not shown).

The switching mechanism shown in Fig. 1 has the advantage over drum type switches, which have been used in circuits similar to Fig. 2, that it is much easier to replace the arcing contacts which ordinarily require more frequent servicing and replacement than do other parts of the system such as, for example, the contacts of the non-arcing duty tap changers 39 and 40. The crank and connecting rod driving linkages for the switches shown in Fig. 1 also give more direct

and positive operation of the switches than could be obtained by the use of separate cams for operating each of the four switch arms 5, 6, 7 and 8.

While there has been shown and described a particular embodiment of the invention, it will be obvious to those skilled in the art that changes and modifications can be made without departing from the invention and therefore it is aimed in the appended claims to cover all such changes and modifications as fall within the true spirit and scope of the invention.

What I claim as new and desire to secure by Letters Patent of the United States is:

An electric switch comprising, in combination, an electrical conducting shaft, four spaced parallel electrical conducting arms pivotally mounted on said shaft, a separate movable contact pivotally mounted on an end of each arm, four insulated fixed contacts for cooperation respectively with said movable contacts, separate springs for biasing each movable contact toward its cooperating fixed contact, a crank shaft having four angularly displaced crank arms, said crank shaft being parallel to said conducting shaft, connecting rods respectively interconnecting said crank arms and said electrically conducting arms, a freely rotatable shaft mounted parallel to said crank shaft, a driving member fixed on said freely rotatable shaft and having a given radius, a fifth crank arm attached to said crank shaft and having a longer radius than said driving member, a connecting rod between said driving member and said fifth crank whereby continued rotation of said freely rotatable shaft in either direction will cause oscillatory rotation of said crank shaft through a predetermined angular range which is substantially less than 360 degrees, the angular displacement of said four crank arms relative to each other and to said fifth crank being such that at one end of said angular range of oscillatory rotation two of said movable contacts engage their cooperating fixed contacts with one of said movable contacts turned about its pivotal mounting against the force of its spring further than the other one and with the other two movable contacts separated from their respective fixed contacts, while at the other end of said range said other two movable contacts engage their respective fixed contacts with one of said other two movable contacts turned about its pivotal mounting against the force of its spring further than the other one and with the first two movable contacts separated from their respective fixed contacts, while at the middle of said range the two movable contacts which are respectively turned furthest about their pivotal mountings at the opposite ends of said range each engage their respective fixed contacts and the remaining two movable contacts are out of engagement with their respective fixed contacts, and an electrical terminal for said switch connected to said electrical conducting shaft.
